COMBINED STILL AND COIL CRACKING

Frank A. Howard, Elizabeth, N. J., assignor to
 Standard Oil Development Company, a corpora-
 tion of Delaware

Application July 25, 1929, Serial No. 380,783

2 Claims. (Cl. 196—58)

This invention relates to improvements in combined still and coil cracking of hydrocarbon oil, particularly that type in which a hot product from the coil is used to heat the oil in the still.

5 A principal object of the present invention is to provide an improved cyclic circulation including coil, still and fractionation means. A clean circulation is secured by removing tar in an expansion zone. Heat from the cracked product 10 is imparted to the oil in the still by indirect heat exchange.

The invention will be fully understood from the following description read in connection with the accompanying drawing in which the figure 15 is a diagrammatic side elevation of preferred equipment.

Referring to the drawing, the equipment comprises a cracking coil 1 located in a furnace setting 2 and discharging through line 3 having a 20 pressure control valve 3a into the lower portion of a vapor separator 4. Oil is passed into the system through a line 27, subsequently described. A line 5, controlled by a valve 6, permits the discharge of tar from the separator.

25 Vapors from the separator 4 are conducted through line 7 and valve 8 into the lower portion of a bubble tower 10, which is provided with the usual bell caps 11, down-flow pipes 12 and top cooling coil 13. Vapors issuing from the bubble tower pass through a line 14 to a condensing coil 15 and receiving drum 16. A distillate outlet 17 and a gas outlet 18 communicate with the drum. Valves 19 and 20 are provided in these outlets respectively. A pressure control valve 21 is provided in line 14 between condenser 15 and tower 10.

30 A still 25 is provided intermediate cracking coil 1 and separator 4 with the line 3 passing therethrough whereby the contents of the still 40 can be heated by the hot oil passing through the line 3. This line can be manifolded or coiled so as to secure more extensive contact surface.

The still is preferably heavily lagged and is set 45 over a furnace 25a. Vapors from the still are passed into the bubble tower through the line 26 in which there is a pressure control valve 26a. Feed oil, together with the heavier constituents 50 condensed from the vaporous product in the bubble tower are introduced into the still through a line 30. A spreader plate 30a is preferably provided to distribute the oil. A valve 31 is provided in line 30. A line 32 connects line 30 thru valve 32a and pump 33 with cracking coil 1, for the introduction of feed oil and condensate into 55 the cracking coil. A line 34 communicates with

the bottom of still 25 and the line 32. A valve 35 is provided in line 34. The still bottoms can be conducted from still 25 through lines 34 and 32 into the cracking coil 1. A line 36 connects line 27 with cracking coil 1 and permits of the introduction of fresh feed oil directly into the cracking coil. A valve 37 is provided in the line 36.

In operating the equipment, feed oil such as gas oil or the like is introduced through line 10 27, bubble tower 10 and lines 30 and 32 into cracking coil 1 and thence into separator 4. The oil is subjected to a temperature of approximately 850°—900° F. in the cracking coil. Tar accumulating in the separator 4 is withdrawn through 15 the line 5. The vapors are withdrawn from the separator through line 7 into the bubble tower 10 where they are rectified and in part condensed by the feed oil, the lighter ends thereof being simultaneously vaporized. The rectified vapors 20 are withdrawn and condensed to form end products of fixed gas and cracked distillate.

The feed oil, together with the heavier constituents obtained from the vapors in the bubble tower, are subjected in the still to temperatures 25 approximating 775° to 800° F., whereby additional cracking of the oil is obtained. Some or all of the heat used for distillation is obtained from the indirect heat exchange effected by the highly heated oil passing through line 3.

30 The oil is preferably maintained under a pressure of approximately 450# per sq. in. while passing through the cracking coil and separator and a pressure of approximately 200 to 400# per sq. in. is preferably maintained in the still and tower. 35 A lower pressure than 450 pounds per square inch can be maintained in the separator and some of the advantages of the invention will be retained. Bottoms are continuously withdrawn from the still through pipes 34 and 32 by means of pump 40 33 or otherwise and pass through the cracking coil 1 where they are raised in temperature approximately 75° to 125° F. thereby vaporizing approximately 60 to 85% of the bottoms when the pressure is reduced as in the separator 4. The 45 highly heated oil and vapors passing through the line 3 supply the heat for cracking and vaporizing the oil in the still, and also offset the heat lost by radiation from the still, and drop in temperature approximately 75° to 125° as a consequence thereof. Heat from other sources may be also supplied to the still, if required.

50 Numerous changes and alternative arrangements may be made within the scope of the ap- 55

pended claims in which it is the intention to claim all novelty inherent in the invention as broadly as the prior art permits.

I claim:

- 5 1. The method of cracking petroleum which comprises introducing said petroleum into a fractionating zone, passing it counter-currently in said zone to vaporous cracking products whereby said petroleum is partially stripped, introducing 10 the residual petroleum into a cracking and distillation zone where it is subjected to conditions suitable for limited cracking and distillation, removing vaporous products from this zone, passing the residual petroleum from this zone to an elongated narrow heating zone in which it is subjected 15 to more severe cracking conditions, conducting the total cracked effluent directly through the said cracking and distillation zone in indirect heat exchange relation thereto without permitting any of said cracked effluent to come in contact with products undergoing cracking in said cracking and distilling zone, passing said cracked effluent to a separator, withdrawing tar from said separator and rejecting it from the system and
- 20

passing vaporous products to said fractionating zone.

2. The method of cracking petroleum, which comprises the cracking distillation of the petroleum at temperature and pressure of the order of 5 775° to 800° F. and 200 to 400 pounds per square inch, taking off vapors, withdrawing unvaporized residues and heating them to cracking temperature and pressure of the order of 850° to 900° F. and above 400 pounds per square inch, passing 10 the heated residues while at cracking temperature in indirect heat exchange relationship with the oil undergoing cracking distillation to heat said oil, separating the residues into vapors and tar in a separation zone maintained under a pressure between 200 and 450 pounds per square inch, 15 withdrawing the tar, stripping light fractions from the petroleum passing to the cracking distillation, by contact with vapors from the cracking distillation and the separation zone and supplying additional heat to the oil undergoing cracking distillation from a source independent of the products of cracking.

FRANK A. HOWARD.
